ABSTRACT OF THE DISCLOSURE

An electrical wrench for tightening nuts, having peripheral ribs, within a switch box. The wrench is adapted to fit within the switch box and has a lever actuated pawl for engaging the ribs of the nut. A ratchet-like motion within a limited arc will cause the pawl to alternately contact the ribs and thereby cause the nut to be tightened. An interchanegable socket is utilized to position the wrench and the pawl relative to the nut.

BACKGROUND OF THE INVENTION

In connection with the installation of electrical wiring in buildings, it customary to embed in the walls and ceilings metal conduits which contain the electrical wires, and to install at intervals throughout the length of the metal conduit, outlets in the form of metal switch boxes which are enclosed by walls, having small openings, on all sides except one through which access is had to the switch and which is usually placed flush with the surface of the wall. The metal conduit enters the switch box through one end and is connected with the switch box by two nuts screwed on the metal conduit and engaging opposite sides of the opening in the switch box wall through which the conduit is projected. The nuts that are usually employed on the interior of the box are formed of an annular rim having peripheral ribs projecting outwardly therefrom, which ribs may be conveniently grasped by an electrician's hand or by a pair of pliers. However, the space within the switch box in which these nuts must be placed is extremely limited and it is very difficult to tighten the nut down upon the metal conduit after it has been loosely positioned or started thereon by hand. Quite often, since a pair of pliers cannot be inserted and used within the limited space of the switch box, a screw driver is placed against the peripheral ribs of the nut and a hammer is used to tap the nut around to a tightened position. This operation is obviously time consuming and dangerous from the standpoint of damaging both the nut and the threads of the metal conduit.

SUMMARY OF THE INVENTION

After the nut has been "started" on the metal conduit by hand, the electrical wrench described hereinafter is placed within the switch box and positively positioned within the open end of the metal conduit and adjacent the periphery of the nut. The operator by simply manipulating an operating lever pivoted to the wrench will cause a pawl to engage the outwardly extending ribs of the nut and a ratchet like action will cause the nut to be tightened down on the metal conduit upon reciprocal movement of the handle in a limited arc. The electrical wrench is adapted to positively position itself with regard to a plurality of different diameter conduits and nuts and is of simple, durable and inexpensive construction.

BRIEF DESCRIPTION OF THE DRAWINGS

FIG. 1 is a perspective view illustrating the electrical wrench;

FIG. 2 is a cut away view along line 2—2 when the wrench is in its folded position;

2

FIG. 3 is a partial cut away view of the wrench in operation; and

FIG. 4 is a view along line 4—4.

DESCRIPTION OF THE PREFERRED EMBODIMENT

Referring now to the drawings wherein like numbers designate like or corresponding parts throughout the several views, there is shown in FIG. 1 an electrical wrench 10 having a handle 11. The handle 11 while shown as being constructed from a channel member which provides light weight and sufficient rigidity and strength to tighten electrical nuts can also be made from solid stock of any cross sectional configuration.

15 Disposed on one end of the handle 11 and projecting substantially perpendicularly therefrom is a shaft 12. The shaft 12 is adapted to fit within the open end of an electrical conduit during utilization of the electrical wrench 10 and is additionally adapted to receive a removable socket means 13. Positioned adjacent the free end of the shaft 12 is a catch 14 which is adapted to allow the socket means 13 to be removably positioned about the shaft 12 while preventing the socket means 13 from falling off until released by an operator. In FIG. 1 the catch 14 is illustrated as a simple ball, however it will be obvious to one skilled in the art that a number of other catches can be utilized.

Extending outwardly from the handle 11 co-planar and adjacent to the shaft 12 is a guide means 16. The guide means comprises a member 17 having a channel 18. The channel 18 extends through the member 17 parallel to the handle 11 and perpendicular to the shaft 12.

30 Disposed intermediate the ends of the handle 11 and pivotally secured thereto at a point behind the guide means 35 16 is an operating lever 19. The operating lever 19 is of a substantially L-shaped configuration, having a bifurcated base portion 20. One branch of the bifurcated base portion is disposed on each side of the handle 11 in sandwiching juxtaposition thereto. The longer, or leg, portion of the lever 19 is constructed from a channel section having a width slightly greater than the width of the handle 11. The lever 19 is pivotally secured to the handle 11 by a fastener 21 which extends through both branches of the bifurcated base portion 20 and the handle 11.

40 45 As shown in FIG. 2 a spring means 22 is positioned between the lever 19 and the handle 11 and held in its correct orientation by the fastener 21. The spring means 22 holds the lever 19 in a normally open position wherein the lever 19 extends upwardly and outwardly from the handle 11 at an acute angle thereto as illustrated in FIG. 1.

50 55 Slidably mounted within the channel 18 of the guide means 16 is a pawl rod 23. The pawl rod 23 extends through the channel 18 and outwardly between the lower edges of the bifurcated base portion 20 to which it is pivotally secured by another fastener 15 which extends through both branches of the base portion 20 and the pawl rod 23. When secured between the base portion 20 and disposed within the channel 18 of the guide means 16, the pawl rod 23 is substantially parallel to the handle 11. The pawl rod 23 has a cross section complementary to the cross section of the channel 18 in order to permit reciprocal sliding action therethrough and has a notch 24 on one end adjacent the shaft 12 for engaging the peripheral ribs of a nut 25 during operation.

60 65 Referring now to FIGS. 1 and 3 which illustrate the socket means 13 in greater detail it will be noted that the socket means 13 consists of an inner tubular member 26 and an outer tubular member 27 fixed to the inner tubular member along its upper end and disposed in coaxial complementary, spaced juxtaposition thereto. The inner tubular member 26 has an inner diameter complementary to the shaft 12 in order that the socket means 13 can be po-

sitioned upon the shaft 12 where it is held in place by the catch 14. The inner tubular member 26 is adapted to fit within the opening in the metal conduit and the nut 25 and the lower edge of the outer tubular member 27 is adapted to rest upon the upper surface of the nut 25.

It will be noted that the length of the outer tubular member 27 should be as long as possible while still terminating adjacent the notch 24 of the pawl rod 23. This is desirable in order to ensure that the lower edge of the outer tubular member 27 will remain in contact with the upper surface of the nut 25 during the entire tightening down operation or in other words during the entire period that it is necessary for the pawl rod 23 to engage the peripheral ribs of the nut 25. The actual diameters of the outer and inner tubular members of the socket means 13 is dependent upon the inner diameter of the metal conduit and the outer diameter of the nut to be tightened. By varying the dimensions of the socket means 13 nuts of different sizes can be accommodated.

The socket means 13 can alternately be constructed of a single tubular member having a stepped inner diameter, the smaller inner diameter being complementary to the diameter of the shaft 12. When the alternate socket means is utilized the shaft 12 in effect replaces the inner tubular member 26 and the larger inner diameter of the stepped tubular member is disposed in coaxial spaced relationship to the shaft.

The space between the inner and outer tubular members 26 and 27 respectively is necessary in order to allow the metal conduit to slide up between the tubular members as the nut 25 is tightened down. The ability of the socket means 13 to accommodate the metal conduit is important because it allows the outer tubular member 27 to remain in contact with the upper surface of the nut 25 at all times until the nut is completely tightened down thereby providing a constant guide for the pawl rod 23.

When the electrical wrench is not in use the lever 19 can be pivoted about the fastener 21 to a folded position wherein the handle 11 is sandwiched between the channel construction of the leg portion of the lever 19. When the lever is in its folded position a stop 28 can be actuated to prevent the lever 19 from springing open until the operator is ready to use the wrench. The stop 28 as illustrated consists of an inverted L-shaped member slidably secured to the handle 11 by the fastener 21. When it is desired to lock the lever 19 in its folded position the lever is pivoted downwardly about the fastener 21 so that there is a gap between the attached end of the lever and the top of the handle 11 and the stop 28 is moved into the gap as illustrated in FIG. 2. When it is desired to use the wrench the stop 28 is moved out of the gap and the lever 19 is urged outwardly to its open position by the action of the spring means 22.

In operation, the stop 28 is released allowing the spring means 22 to urge the operating lever 19 to its outward or open position. The nut 25 is hand threaded upon the metal conduit and the correct size socket means 13 is slipped over the shaft 12 where the catch 14 holds it in position. The inner tubular member 26 of the socket means 13 is inserted within the metal conduit until the lower edge of the outer tubular member 27 rests upon the upper surface of the nut 25 at which time the upper end of the metal conduit is disposed in the space between the inner and outer tubular members 26 and 27. The operator squeezes the operating lever 19 downwardly causing the bifurcated base portion 20 of the lever 19 to pivot about the fastener 21. The pivoting of the base portion 20 in turn causes the pawl rod 23 to slide forward through the channel 18 in the guide means 16 until the notched end of the rod engages the peripheral ribs of the nut 25. When the pawl rod 23 is in engagement with the nut 25 the wrench is rotated in an arc which is limited by the dimensions of the switch box, thereby causing the nut to rotate in conjunction therewith. When the wrench can no longer be rotated the operator releases the operating lever 19 thereby allowing the spring means 22 to cause the disen-

gagement of the pawl rod from the nut. The wrench is then rotated in a reverse direction and the operation is repeated until the nut is tightened down upon the metal conduit. As the nut is tightened down upon the metal conduit, the metal conduit moves up within the space between the inner and outer tubular members.

I claim:

1. An electrical wrench for tightening nuts having peripheral ribs, said wrench comprising:
10 a handle having a shaft extending substantially perpendicularly from one end thereof;
15 an operating lever pivotally secured to said handle intermediate its ends;
a pawl rod pivotally secured to said operating lever and adapted to move into substantially perpendicular juxtaposition to said shaft when said lever is manipulated; and
20 a socket means mounted on said shaft and adapted to position said wrench relative to the nut whereby said pawl rod will engage the ribs of the nut when said pawl rod is moved into juxtaposition to said shaft.
2. An electrical wrench in accordance with claim 1 further comprising a spring means disposed in cooperating relationship to said handle and said operating lever, said spring means adapted to bias said lever away from said handle.
3. An electrical wrench in accordance with claim 1 further comprising a guide means secured to said handle, coplanar and adjacent to said shaft, said guide means adapted to receive said pawl rod and guide said pawl rod to a substantially perpendicular relationship to said shaft when said pawl rod is moved into juxtaposition thereto.
4. An electrical wrench in accordance with claim 1 wherein said socket means comprises:
35 an inner tubular member; and
an outer tubular member secured to said inner tubular member along its upper end and disposed in coaxial, complementary, spaced juxtaposition thereto.
5. An electrical wrench in accordance with claim 4 wherein said outer tubular member terminates adjacent said pawl rod.
6. An electrical wrench in accordance with claim 1 further comprising a stop secured to said handle and adapted to be inserted between said lever and said handle when said lever is moved to a folded position adjacent said handle, whereby said lever is secured against movement until said stop is released.
7. An electrical wrench in accordance with claim 1 further comprising a catch disposed on said shaft and adapted to releasably support said socket means thereon.
8. An electrical wrench in accordance with claim 1 wherein said socket means comprises a tubular member having a stepped inner diameter, the smaller inner diameter adapted to engage said shaft and thereby position the larger inner diameter of said tubular member in coaxial, complementary, spaced relationship to said shaft.
9. An electrical wrench in accordance with claim 1 wherein said operating lever is of a substantially L-shaped construction and is pivotally secured to said handle by a bifurcated base portion, said pawl rod being secured to the free end of the base portion and said spring means is disposed between the leg of the lever and the handle, said spring means biasing said leg of said lever away from said handle and at an acute angle thereto.
10. An electrical wrench for tightening nuts having peripheral ribs, said wrench comprising:
70 a handle having a shaft extending substantially perpendicularly from one end thereof;
a guide means secured to said handle coplanar and adjacent to said shaft, said guide means having a channel therein perpendicular to said shaft;
an operating lever pivotally secured to said handle intermediate its ends;
a spring means disposed between said handle and said

lever and adapted to bias said lever away from said handle;
 a pawl rod pivotally secured to said lever and adapted to slide through the channel in said guide means, whereby said pawl rod is moved into juxtaposition to said shaft when operating lever is manipulated to overcome the biasing of said spring means; and
 a socket means mounted on said shaft, said socket means having an outer tubular member adapted to rest upon the upper surface of the nut and thereby position said wrench relative to the nut whereby said pawl rod will engage the ribs of the nut when said pawl rod is moved into juxtaposition to said shaft.

11. A method of tightening nuts having peripheral ribs on a conduit with an electrical wrench comprising the steps of:

10 positioning said nut on said conduit;
 placing a tubular member, secured to said wrench, over said conduit until the lower edge of said tubular

15

member abuts the upper surface of said nut and a portion of said conduit is disposed internally of said tubular member;
 moving a pawl rod, cooperatively secured to said wrench, into contact with the peripheral ribs of said nut; and
 rotating said wrench, whereby said pawl rod and said nut rotates with said wrench.
